LIQUID DISPENSER

Harvey L. Friedman, 6361 Fairhaven Road,
Mayfield Heights, Ohio 44124

Continuation-in-part of abandoned design application Ser.
No. 169,160, Aug. 4, 1971. This application Nov. 10,
1971, Ser. No. 197,592

Term of patent 14 years

Int. Cl. D6—06

U.S. Cl. D6—95

FIG. 6

FIG. 7

FIG. 8

FIG. 10

FIG. 9

FIG. 1 is a top plan view of a liquid dispenser embodying my new design.

FIG. 2 is a front elevational view thereof.

FIG. 3 is a side elevational view thereof.

FIG. 4 is a bottom plan view thereof.

FIG. 5 is a rear elevational view thereof.

FIG. 6 is a top plan view of a modified form of the liquid dispenser shown in FIG. 1.

FIG. 7 is a front elevational view of FIG. 6.

FIG. 8 is a side elevational view of FIG. 6.

FIG. 9 is a bottom plan view of FIG. 6.

FIG. 10 is a rear elevational view of FIG. 6.

This is a continuation-in-part of design application Ser. No. 169,160, filed Aug. 4, 1971, now abandoned.

I claim:

The ornamental design for a liquid dispenser, as shown and described.
